UNITED STATES PATENT OFFICE

2,472,643

SHOE STITCH REMOVER

Alfred Barbagallo, West Palm Beach, Fla., assignor of one-half to Andrew James Longo, Palm Beach, Fla.

Application July 18, 1947, Serial No. 761,756

5 Claims. (Cl. 12—103)

1

This invention relates to devices to be used by shoemakers in connection with the resoling of shoes.

In the art of shoemaking when a pair of shoes is to be resoled the old worn sole is removed so that the welt is left upon the upper, for the attachment thereto by sewing, of the new shoe sole. It is customary in removing the old sole to run a knife blade between the worn sole and the welt to cut away the stitching. As a result of this the welt is left with part of the original stitching in it and when the new sole is applied and is sewn in place these pieces of the original stitching, if not removed, give an unsightly or messy appearance to the resoling job but since it is rather a tedious operation to remove the particles of the old stitching the majority of shoemakers will not do this unless the customer pays extra for the work.

It is an object of the present invention to provide an implement of simple design and of a character to be economically manufactured, which may be employed for easily and quickly removing from the shoe welt the remaining portion of the old stitching after the worn sole has been cut away.

Another object of the invention is to provide an implement of the character stated which, in addition to being provided with means for removing the old remaining stitch pieces or sections, is adapted to roughen or abrade the under surface of the welt so that when the new sole is placed in position the cement which is ordinarily used to obtain a firm bond between the new sole and the old portion of the shoe, can be made to adhere strongly to the welt.

Another object of the invention is to provide an implement of the character stated which comprises a pair of spaced parallel blades mounted upon a handle, one of the blades having a pair of short inwardly directed scraper blades while the other one of the two spaced blades has its inner face roughened or toothed to provide a rasp, the space between the two blades being such as to snugly receive the edge of the welt of the shoe.

The invention will be best understood from a consideration of the following detailed description taken in connection with the accompanying drawings forming a part of the specification, with the understanding, however, that the invention

2

is not to be understood as limited to the exact details of construction shown and described since obvious modifications will occur to a person skilled in the art.

5 In the drawing

Figure 1 is a view in front end elevation of an implement constructed in accordance with the present invention.

10 Figure 2 is a view in side elevation of the same.

Figure 3 is a view in top plan of the implement.

Figure 4 is a sectional view taken substantially on the line 4—4 of Figure 2 looking down upon the rasp.

15 Figure 5 is a view in perspective showing the manner in which the implement is used.

Referring now more particularly to the drawing numeral 10 generally designates the handle of the present implement, the forward end of which is provided with the usual ferrule 11 to strengthen

20 the same.

At the forward end of the handle is fixed the head 12 which comprises two relatively wide flat jaw plates 13 and 14 joined together by a relatively narrow intermediate portion 15 which positions against the end of the handle and is apertured to receive a securing screw or pin 16 which is fastened into the end of the handle whereby the head extends forwardly therefrom. It will thus be seen that the head when viewed in side elevation as shown in Figure 2, is substantially U-shaped in form and the jaw plates are connected only at the inner sides by the narrow yoke portion 15 which is formed integrally with the jaw plates.

25 30 35 The upper jaw plate 13 carries the two inwardly directed relatively long scraping blades 17. These blades which are directed toward the opposite plate 14 are relatively narrow, the space between the edges α of the blades and the opposite jaw plate 14 being approximately equal to the thickness of the welt of a shoe.

40 45 The inner face of the lower jaw plate 14 is formed to provide a rasp 18. This rasp extends from one side of the plate 14 to the other and is of substantial width so that in the use of the device it will scrape and roughen the underface of the shoe welt so as to prepare it for the reception of the cement which is employed for securing the new sole to the shoe.

50 While the scraping blade 17 may be formed in

any suitable manner, a convenient method is by punching in a portion of the plate 13 as shown in Figure 3, employing the inturned or inpunched part of the plate as the scraping blades. These blades may be suitably sharpened, if desired, to perform the desired function.

Figure 5 illustrates the application of the present invention. In this figure there is shown a shoe 19, the welt of which is designated 20. As shown in the use of the implement the wide forward edges of the plates 13 and 14 of the implement head are moved toward the welt so that the latter is received between the roughened or rasp surface 18 of the bottom plate and the scraping blades 17 which are carried by and extend inwardly from the top plate. The blades 17 are of a length to substantially equal the width of the welt and when the welt is disposed between the plates 13 and 14 the blades 17 will be in more or less firm contact with the top of the welt and when the implement is then moved back and forth as indicated by the arrows in Figure 5 the blades 17 will dig or pull out the loops or pieces of the old stitching by which the worn sole was secured to the welt. At the same time this operation is being performed the rasp 18 will be contacting the under surface of the welt and roughening the same in the manner required for obtaining the desired perfect bonding by means of cement, between the underside of the welt and the applied new sole. Thus it will be seen that after using the implement of the present invention when the new sole is sewn in place only the new stitching will be seen and no remnants of the old stitching will remain to produce an unsightly piece of work.

I claim:

1. An implement for removing old stitching particles from the welt of a shoe, comprising a handle, a plate attached to the handle, a blade carried by the plate and extending therefrom in a plane perpendicular to a face thereof, said blade being of a length to extend the width of the

shoe welt to effect the removal of the old stitching particles when moved lengthwise of and in contact with the top surface of the welt, and a second plate attached to the handle and having spaced parallel relation with the face of the first plate from which the blade projects, said plates being spaced apart to snugly receive the shoe welt between the edge of the blade and the inner face of the second plate.

2. An implement of the character as stated in claim 1 in which the inner face of the second plate is formed so as to provide a rasp for roughening the under face of the welt as the plates are moved lengthwise of the welt with the welt disposed between the plates.

3. An implement of the character stated comprising a relatively long handle member, a pair of relatively wide plate members secured in spaced parallel relation to an end of the handle, a pair of relatively narrow blades carried by one of the plates and extending inwardly therefrom toward the other plate, said blades having their inner edges spaced from the said other plate a distance to receive the welt of a shoe between their inner edges and said other plate.

4. An implement of the character stated in claim 3 wherein the inner face of the said other plate is formed to provide a rasp.

5. An implement of the character stated in claim 3 wherein said blades are of a length substantially equal to the width of the welt across which they extend in the operation of using the implement.

ALFRED BARBAGALLO.
